US00D960302S

(12) **United States Design Patent** (10) Patent No.: **US D960,302 S**
Cocks et al. (45) Date of Patent: **** Aug. 9, 2022**

(54) **SHOWER HEAD**(71) Applicant: **Phoenix Industries Pty Ltd.**,
Bayswater (AU)(72) Inventors: **Andrew John Cocks**, Bayswater (AU);
Ban Hsi Liu, Bayswater (AU)(73) Assignee: **Phoenix Industries Pty Ltd**, Bayswater
(AU)(**) Term: **15 Years**(21) Appl. No.: **29/736,779**(22) Filed: **Jun. 3, 2020****Related U.S. Application Data**(63) Continuation of application No. 29/630,825, filed on
Dec. 22, 2017, now Pat. No. Des. 888,195.**Foreign Application Priority Data**

Jun. 28, 2017 (AU) 201713952
 Jun. 28, 2017 (AU) 201713953
 Jun. 28, 2017 (AU) 201713954
 Jun. 28, 2017 (AU) 201713955

(51) **LOC (13) Cl.** ..... **23-01**(52) **U.S. Cl.**
USPC ..... **D23/213****Field of Classification Search**

New Rain Shower Heads for Your Bathroom posted uakc.com.
 Available date: Aug. 9, 2014 [site visited Sep. 14, 2021] Available:
 <<https://www.uakc.com/blog/rain-shower-heads/>> (Year: 2014).*

(Continued)

Primary Examiner — Kevin K Rudzinski*(74) Attorney, Agent, or Firm* — Womble Bond Dickinson
(US) LLP**(57) CLAIM**

The ornamental design for a shower head, as shown and described.

DESCRIPTION

FIG. 1 is a perspective top view of a shower head according to our new design;

FIG. 2 is a perspective bottom view thereof;

FIG. 3 is a side view thereof;

FIG. 4 is a front view thereof;

FIG. 5 is a top view thereof; and,

FIG. 6 is a bottom view thereof.

1 Claim, 6 Drawing Sheets# US D960,302 S
